UNITED STATES PATENT OFFICE

173,161

RADAR INDICATOR

John S. Kendrick, Concord, Mass., assignor to
Raytheon Manufacturing Company, Newton,
Mass., a corporation of Delaware

Application August 19, 1953, Serial No. 26,518

Term of patent 14 years

(Cl. D26—5)

To all whom it may concern:

Be it known that I, John S. Kendrick, a citizen of the United States, residing at Concord, in the county of Middlesex and Commonwealth of Massachusetts, have invented a new, original, and ornamental Design for a Radar Indicator, of which the following is a specification, reference being had to the accompanying drawings, forming part hereof, in which

Fig. 1 is a side elevation view of the radar indicator showing my new design;

Fig. 2 is a top plan view; and

Fig. 3 is a front elevation view.

I claim:

The ornamental design for a radar indicator, substantially as shown.
